UNITED STATES PATENT OFFICE.

GEORGE WHARTON EDWARDS, OF NEW YORK, N. Y., ASSIGNOR TO FUNK & WAGNALLS COMPANY, OF NEW YORK, N. Y.

DESIGN FOR A BOOK-COVER.

SPECIFICATION forming part of Design No. 35,291, dated November 19, 1901.

Application filed October 18, 1901. Serial No. 79,171. Term of patent 14 years.

To all whom it may concern:

Be it known that I, GEORGE WHARTON EDWARDS, a citizen of the United States, and a resident of the city of New York, borough of Manhattan, in the county and State of New York, have invented and produced a new and original Design for a Book-Cover, of which the following is a specification, reference being had to the accompanying drawing, forming part thereof, in which the figure is a face view of a book-cover showing my design.

The leading feature of the design consists in the ornamentation of the book-cover made in the subject-matter of the accompanying illustration.

The design in its entirety consists of the sides A A and the back B, of which the sides have a like ornamentation, consisting of panels C C', surrounded by an approximately rectangular foliate border D, the panel C appearing with the representation of an open book E over a torch E' and within a wreath E², the torch, book, and foliage in the border appearing in intaglio, the said border having the foliage appearing as emanating from the

relief representation of an open book D' over an intaglio torch D², both located at the middle of the top and bottom of the border D, the said back B appearing with panels F F' F², of which the central panel F is ornamented by the representation of an open book F³ over a torch F⁴ and within a wreath F⁵, the latter book and torch appearing in intaglio, and above the panel F and below the panel F² appear foliate bars G G', having the foliage in intaglio, the bar G' also appearing at its middle with a small panel H in relief.

Having described my invention, what I claim as new, and desire to secure by Letters Patent, is—

The design for a book-cover as herein shown and described.

In testimony whereof I have signed my name to this specification in the presence of two subscribing witnesses.

GEORGE WHARTON EDWARDS.
